SEPARATOR

John P. Mahoney and Leland E. Long, South Bend, Ind., assignors to Bendix Aviation Corporation, South Bend, Ind., a corporation of Delaware

Application June 21, 1933, Serial No. 676,980

4 Claims. (Cl. 209—452)

This invention relates to separators for ore and the like, and more particularly to a machine for separating values from finely divided ores.

5 An object of the invention is to provide a simple and inexpensive mechanism for the separation of finely divided solids.

A further object of the invention is to provide a portable mechanism requiring a minimum 10 of power and yet efficient in its operation.

Further objects and advantages of the invention will be apparent from the following description, taken in connection with the appended drawings, in which:

15 Figure 1 is a side elevation of a machine embodying the invention;

Figure 2 is an end view of the same as seen from the right of Figure 1, but with parts broken away to disclose the remaining mechanism more clearly;

20 Figure 3 is an enlarged sectional view of the rotary concentrating member;

Figure 4 is a front view of the same;

Figure 5 is a longitudinal section through a 25 modified form of rotary concentrating member;

Figure 6 is a fragmentary view showing a modified form of baffle; and

Figure 7 is a similar view of another modified form of baffle.

30 The machine illustrated in Figures 1 and 2 comprises generally a base 10, a separator 12, a concentrator 14, a power unit 16, which may be an internal combustion engine, a water pump 18, and a housing 20 enclosing the other elements as shown.

35 The separator 12 comprises a hopper 22 into which the ore is delivered by any suitable means (not shown). A series of nozzles 24 deliver streams of water upon the ore in the hopper, 40 which assist in moving the ore downwardly into a coarse inclined trommel screen 26. Here the coarser rocks are rejected by the screen and passed to a trough 28 and thence to a discharge chute 30, which leads to an inclined endless conveyor 32 of any suitable type, preferably supported by a brace 33. Screen 26 is surrounded by successively finer mesh trommel screens 34 and 36, designed to eliminate the coarser aggregate and discharge it at chute 30. A pipe 37 45 extends into screen 34 and is provided with spaced jets which discharge water onto the aggregate during the screening operation. Each screen is provided at its discharge end with an annular trough 28, designed to retain the aggregate

gate of relatively high specific gravity, such as nuggets.

The screens 26, 34, and 36 are mounted within a cylindrical drum 38, which is inclined similarly to the screens and which receives the fine 5 aggregate, water and silt passed by screen 36. Drum 38 is rotatably carried by grooved rollers 40 which engage hoops 42 extending circumferentially around the drum. One or more of the rollers are driven by a shaft 44 which takes 10 its power through a chain 46 from the power plant 16.

Drum 38 discharges into a chute 48 which leads through a pipe 50 to the concentrator 14, now to be described. The concentrator comprises a conical member 52 having an exterior hoop 54 which engages three idling rollers 56 which support it in rotatable relation. Rollers 56 are carried by a polygonal frame 58 which, by means of brackets 59, is pivotally mounted 20 on a shaft 60 journaled in trunnions 62. Shaft 60 is driven from the power plant 16 through the medium of a reduction gear 64 of any known and suitable construction. It carries a bevel gear 66 which engages a ring gear 68 fixed to 25 a bracket 69 which is in turn fixed to or formed integral with the conical member 52, and thus rotates member 52 when the machine is in operation. In order to adjust the inclination of the axis of member 52, a link 70 is pivoted to the 30 lower portion of frame 58 and has formed therein a longitudinal bore threaded to receive a correspondingly threaded shaft 72 which is journaled in a bracket 74 and provided at its outer end with a handwheel 76.

35 The interior of member 52 is provided on its conical surface with ridges or lands 78 defining intervening grooves 80 for the reception of the fine aggregate. The lands 78 extend generally perpendicular to the inner surface of 40 52 and are tapered as shown. The height of the lands gradually decreases from the base of the cone toward the apex. Preferably, there are a plurality of lands or parallel lands (six in the embodiment illustrated in Fig. 3) extending from the base 45 toward the apex of the cone in parallel relation and terminating in a discharge mouth provided with a flaring flange 82. A member 84, of generally conical shape, is secured to the base of member 52 and forms therewith a reservoir 86 50 for the reception of ore and water from pipe 50. Member 84 is provided with a flared outlet flange 88, as shown, for the discharge of aggregate from the concentrator 14.

Additional water at constant head is supplied 55

to the aggregate during its passage through the concentrator 14 by the mechanism now to be described. Pump 18 has a discharge pipe 90 leading to pipe 37. A branch pipe 92 leads upwardly from pipe 90 and communicates at its upper end with nozzles 24. At its lower end, pipe 92 is provided with a nozzle 94 which is controlled by a valve 96 and discharges into a reservoir 98 having an overflow pipe 100. When valve 96 is properly adjusted, the water in reservoir 98 is maintained at or near the level of overflow pipe 100. From reservoir 98 a feed pipe 102 leads to the interior of concentrator 14, where it has a horizontally extending portion 104 provided with a series of jets 106 which may be aligned with the grooves 80 in such manner that, in a given position, each groove receives the discharge from one jet. Jets 106 are preferably of decreasing capacity toward the discharge mouth 82, and may, if desired, be provided with individual adjusting valves to control the discharge of each jet separately. The pipe 102 is preferably supported by a brace 105 and is provided with a flexible section 103, to permit movement of the portion 104 in the adjustment of the machine.

A hopper 108 is provided to receive the values from mouth 82, and leads through a vertical chute 110 to a receptacle of any suitable construction (not shown). The discharge pipe 50 is provided with a telescoping discharge spout 112, having an exterior flange 113 provided with a slot to receive a transverse rod 114. The rod 114 is carried by spaced arms 115 which are fixed to brackets 59, so that when the axis of member 52 is adjusted by handwheel 76 the spout 112 will ride up or down on pipe 50 and thus maintain the lower end of the spout at a fixed distance from the bottom of reservoir 86. A paddle 116 is also carried by rod 114 and projects into reservoir 86 in such position as to agitate or plow up the aggregate therein as the separator is rotated.

In operation, the ore, consisting of mixed aggregate, is fed into hopper 22 by any suitable means, and is thence fed by gravity, assisted by the washing action of the water from nozzles 24, to the separator 12. Here the aggregate is separated into (1) fine aggregate, passed by screen 36, (2) coarse aggregate, rejected by any of screens 26, 34, or 36 and not retained by troughs 28, and (3) coarse aggregate retained by troughs 28. The coarse aggregate is delivered to conveyor 32 as tailings, and the material retained by troughs 28 is manually removed and inspected for values.

The fine aggregate, mixed with a considerable amount of water from nozzles 24 and pipe 37, then passes through chute 48 to the concentrator 14. The speed and inclination of the concentrator have been adjusted to give the desired separation for the particular ore being processed, higher speed tending toward more rapid but less selective separation, and inclination of the separator axis downwardly (in the clockwise direction as viewed in Figure 3) tending toward increasing the amount of tailings and decreasing the volume of values separated out at the mouth 82. The fine aggregate is taken up by the various grooves and progressively moved toward the mouth 82, since it is retained by gravity at the bottoms of the grooves. During its progression upward, however, it is continuously agitated and tumbled by the rotation of the member 52 and is washed by the water discharged by the jets 106, so that the heavier particles, containing the

values, gravitate to the bottoms of the grooves, whereas the lighter portions are washed over the tops of the lands back to the reservoir 86, from which they overflow as tailings onto a horizontal reach 33 of the conveyor 32 in the manner clearly shown in Figure 3.

The concentrator shown in Figure 5 is generally similar to that above described, except as hereinafter noted. The conical member 120 has a more gradual taper than member 52, although the lands and grooves thereof may be similar to those of member 52. Two hoops 122 are provided at opposite ends of the member 120, and are adapted to engage the rollers of a driving and adjusting mechanism similar to that above described. An air nozzle 124 projects into the discharge mouth 126 of the member 120 and is supplied with compressed air from a suitable source (not shown). Nozzle 124 discharges a blast of air over the tops of the lands, which carries with it the lighter particles of aggregate, discharging the same through the open end 128 of the conical member, leaving the heavier metal bearing particles to be discharged at mouth 126. The apparatus is therefore adapted for use as a dry concentrator, although it may be used in wet concentration as well, if desired.

The members 52 and 120 may be formed of cast iron or steel, the lands being formed integral therewith and shaped by a turning operation. In Figures 6 and 7, however, are shown alternative ways of forming the lands. The lands 130 of Figure 6 are formed of hard rubber, synthetic resin or resilient non-metallic material, preferably molded in strips and inserted in a shell 132 of conical form. In the embodiment shown in Figure 7, the lands 134 are formed of strips of rolled metal of L-shaped cross section, which may be flexible enough to permit them to be bent as they are inserted in the conical shell 136. Flat strips 138 are secured at the ends of the shell 136 in such relation as to hold the strips 134 in position.

Although the invention has been described with particular reference to certain specific embodiments thereof, it is capable of many variations, and is not intended to be limited except in accordance with the terms of the following claims.

We claim:

1. An ore separator comprising a substantially horizontal axis, rotary hollow conical member having steeply sloping sides making an angle with the axis over forty-five degrees and continuous spiral grooves on its inner surface to receive ore, said spiral grooves being formed by a separately formed hard rubber rib member extending spirally around the interior of said conical member, a member fixed to the conical member and including a radial inwardly-extending flange cooperating with the peripheral portion of the member to form a reservoir, and means for rotating the conical member about its axis, said flange and member operating to form an annular reservoir during rotation of the member about a horizontal axis.

2. An ore separator comprising a substantially horizontal axis, rotary hollow conical member having steeply sloping sides making an angle with the axis over forty-five degrees and continuous spiral grooves on its inner surface to receive ore, a member fixed to the conical member and including a radial inwardly-extending flange cooperating with the peripheral portion of the member to form a reservoir, means for

rotating the conical member about its axis, said flange and member operating to form an annular reservoir during rotation of the member about a horizontal axis, and means for tilting 5 said axis slightly from the horizontal to vary the operation of the separator.

3. An ore separator comprising a substantially horizontal axis, rotary hollow conical member having steeply sloping sides making an angle 10 with the axis over forty-five degrees and continuous spiral grooves on its inner surface to receive ore, a member fixed to the conical member and including a radial inwardly-extending flange cooperating with the peripheral portion of 15 the member to form a reservoir, means for rotating the conical member about its axis, said flange and member operating to form an annular reservoir during rotation of the member about a

horizontal axis, and means associated with said conical member for supplying water thereto at a constant head.

4. An ore separator comprising a substantially horizontal axis, rotary hollow conical member 5 having steeply sloping sides making an angle with the axis over forty-five degrees and continuous spiral grooves on its inner surface to receive ore, a member fixed to the conical member and including a radial inwardly-extending 10 flange cooperating with the peripheral portion of the member to form a reservoir, and means for rotating the conical member about its axis, said flange and members operating to form an annular reservoir during rotation of the member 15 about a horizontal axis.
